Inventor:

UNITED STATES PATENT OFFICE.

SAMUEL R. BAILEY, OF AMESBURY, MASSACHUSETTS.

SHAFT-SHACKLE FOR VEHICLES.

SPECIFICATION forming part of Letters Patent No. 703,365, dated July 1, 1902.

Application filed January 25, 1902. Serial No. 91,239. (No model.)

To all whom it may concern:

Be it known that I, SAMUEL R. BAILEY, a citizen of the United States, and a resident of Amesbury, in the county of Essex and State 5 of Massachusetts, have invented certain new and useful Improvements in Shaft-Shackles for Vehicles, of which the following is a specification.

This invention relates to improvements in 10 shaft-shackles for vehicles, and has for its object a device of improved and simplified construction capable of being readily applied to and detached from the clip.

My invention consists in the features and 15 in the construction and arrangement of parts hereinafter described, and definitely pointed out in the claims following the description, reference being had to the accompanying drawings, forming a part of the specification, 20 wherein—

Figure 1 is a front elevation of my improved shaft-shackle, showing the same applied to a thill-coupling of a vehicle-axle. Fig. 2 is a longitudinal section on the line 2 2 shown in Fig. 25 1. Fig. 3 is a detail front elevation of the inner end of the shaft-iron. Fig. 4 is a cross-section on the line 4 4 shown in Fig. 2, and Fig. 5 is a detail rear view of the adjustable jaw shown as removed from the shaft-iron.

Similar letters refer to similar parts wherever they occur on the different parts of the drawings.

Referring to the drawings, A indicates one 35 suitable manner to the shaft-iron B.

The shaft-iron B is provided at its rear or inner end with a preferably semicircular jaw b, which, in connection with an adjustable pivoted preferably semicircular jaw C, is 40 adapted to encompass the thill-coupling bolt D or an elastic sleeve d, located thereon, as shown.

The bolt D is pivotally connected to the ears E E of the clip E', which is secured to 45 the carriage-axle F by means of the plate G and nuts e e, as is common in devices of this kind.

The rear inner face of the thill-iron B is provided with a cylindrical recess b', and from 50 the central bottom portion of such recess projects an internally-screw-threaded sleeve b" or nut, which is preferably formed integral

with the thill-iron B, as shown, or may be attached thereto in any desired or suitable manner.

The adjustable jaw C is provided at its inner end with a sleeve C', which is guided and longitudinally adjustable in the cylindrical recess b' in the shaft-iron B, as well as on the sleeve b", secured to or forming a part of 60 said shaft-iron. Within the said sleeve C' is journaled a screw-threaded bolt H, which engages with the internally-screw-threaded sleeve or nut b", as shown in Figs. 2 and 4.

To the outer end of the screw H is secured 65 in a suitable manner an actuator H', preferably made in the form of a circular wheel or disk; but I wish to state that I do not desire to confine myself to this exact form or construction of said actuator or adjuster, as it 70 may be made in the form of a lever or thumb-piece of any desired shape without departing from the essence of my invention. In practice I prefer to provide such actuator or lever with one or more perforations h h h, adapted 75 to receive a strap I, connected to the thill-coupling plate G by passing it through a slotted perforation g in the latter, as shown in Fig. 2, which strap serves, when connected to the plate G and adjuster H', as a means to 80 prevent the latter from rotation.

The screw H is free to turn loosely within the sleeve C' in the adjustable jaw C, but is prevented from having any longitudinal motion therein by means of a collar h' on the 85 upper end of said screw H, journaled in a groove C" on the sleeve C', as shown in Figs. 2 and 4. Such groove C" is preferably made by turning up a lip over the collar h' or in any other suitable or equivalent manner, so 90 as to permit the screw H to rotate freely in the sleeve C' without moving longitudinally therein. By this arrangement the jaw C and its sleeve C' are caused to move in and out relative to the shaft-iron B and its jaw b during the rotary adjustment of the actuator or lever H' and its screw H.

To couple the thill to the bolt of the axle-clip it is only necessary to place the jaw b over the thill-coupling bolt or its rubber 100 sleeve and then turn the jaw C upon the sleeve C' as a pivot until it alines with the jaw b. The screw H is then screwed into the internally-screw-threaded sleeve or nut b"

by turning the actuator H' until the jaws C and b encompass the clip-bolt D or its rubber sleeve, and will thus be held firmly and securely thereon. To uncouple the device, this 5 operation has merely to be reversed and the jaw C swung to a position diametrically opposite to that shown in the drawings.

This invention is very advantageous for several reasons, among which may be mentioned: The adjusting device is constructed in such a manner as to be entirely protected from water, dirt, &c., whereby rusting and clogging of the parts are prevented. The screw of the adjusting device is not liable to bend 10 or bind, on account of the sleeve on the adjustable jaw being guided in a socket or recess in the shaft-iron. By having the adjuster provided with one or more apertures adapted to be connected to the thill-coupling or shaft 15 by means of a strap the adjuster is prevented from turning loose, thus preventing the spreading of the jaws in which the thill-coupling bolt is journaled. By means of said screw-actuated adjuster the movable jaw may be 20 closed relative to the lower jaw and the coupling-bolt or its rubber sleeve with just as little force as necessary for accomplishing the 25 desired result.

Having thus fully described the nature, 30 construction, and operation of my invention, I wish to secure by Letters Patent and claim—

1. In a shaft-shackle, the combination with the thill-iron terminating at its extremity in

a jaw b, and provided on its inner face with an internally - screw - threaded cylindrical 35 sleeve or nut b'', of the screw-threaded bolt H, engaging said nut and provided with an adjuster, and the jaw C journaled on said bolt and adapted to encompass the bolt D, or cushion d, as set forth.

2. In a shaft-shackle, the combination with the thill-iron terminating at its extremity in a jaw and recessed at b' of an internally-screw-threaded cylindrical nut or sleeve b'', projecting from said recessed face, the screw-threaded bolt H engaging said nut and provided with an adjuster, and the jaw C journaled on said bolt and adapted to encompass the bolt D, or cushion d, as set forth.

3. In a shaft-shackle, the combination with the thill-iron terminating at its extremity in a jaw b, and recessed on its inner face at b', of an internally-screw-threaded cylindrical sleeve or nut b'' projecting from said recessed face, the screw-threaded bolt H, engaging 55 said nut and provided with an adjuster H', and means for connecting the latter to the shaft or thill-coupling and the jaw C journaled on said bolt H, and adapted to encompass the bolt D, or cushion d, as set forth.

In testimony whereof I have affixed my signature in presence of two witnesses.

SAMUEL R. BAILEY.
